CLAIM

We claim the ornamental design for an in-wall switch, as shown and described.

DESCRIPTION

FIG. 1 is a top perspective view of an in-wall switch; FIG. 2 is a front elevation view thereof; FIG. 3 is a right side elevation view thereof where the left side is a mirror image of the right side; FIG. 4 is a top plan view thereof; and, FIG. 5 is a bottom plan view thereof. Broken lines in the drawings show environment and form no part of the claimed design.
